MOLD VIBRATOR

Charles Dietrichs, Little Ferry, N. J., assignor to
 Walker Cement Products, Inc., Little Ferry,
 N. J., a corporation of New Jersey

Application February 24, 1930, Serial No. 430,764

6 Claims. (Cl. 25—41)

This invention relates to mechanical vibrators for molds, particularly molds for articles made of cement, such as building blocks, drain tiles, and the like.

The object of the invention is to provide a mechanical vibrator for vibrating the mold and causing a proper settling of the cement mixture while the mold is being filled, thereby obviating the necessity of tamping, and securing a more uniform product than can be otherwise obtained.

A further object of the invention is to provide a molding apparatus for molding drain tile embodying means for finishing off the upper edge of the drain tile after the mold is filled and the cement has been caused to settle by the action of the vibrator, whereby no further operation is required on the drain tile after it is removed from the vibrator.

In the accompanying drawings I have illustrated several practical embodiments of my invention.

In said drawings,

Fig. 1 illustrates in perspective a vibrator wherein the vibrating element is a plain table adapted to receive molds of any description.

Figs. 2, 3 and 4 are detail sectional views on the correspondingly numbered lines of Fig. 1;

Fig. 5 shows in vertical section a modified form of vibrator adapted primarily for pipe molds but otherwise substantially of the same construction as the vibrator shown in Fig. 1;

Fig. 6 shows in vertical section a modified form of pipe mold vibrator wherein the core as well as the outside shell is vibrated;

Fig. 7 is a detail sectional view on the correspondingly numbered line of Fig. 6; and

Fig. 8 is a sectional view of my improved pipe mold vibrator equipped with an end finishing mechanism to thereby produce a complete pipe molding machine.

Referring to the drawings, particularly to Fig. 1, 1 indicates the supporting members for the vibrator here shown as angle irons rigidly bolted to a cement or other suitable base. Attached to each corner of the two angle irons 1 are vertical angles 2 forming the legs of the frame and supported at the upper ends of the vertical angles are side frame members 3 on which the vibrating table 4 is directly supported. The vibrating table consists of a steel plate extending from one side member 3 to the other and held loosely in position thereon by tapered pins 5 at the corner of the plate. The pins 5 are set in the flanges of the side members and project through rubber plugs 6 cemented or otherwise secured to the top of the

frame members. The holes through which the pins pass are larger than the pins so as to permit a slight lateral play of the table.

Fastened to the under side of the table 4 are a pair of flat steel springs 9 whose free ends rest on ratchets 10 carried by a shaft 11 which is mounted in journals 12 at the opposite ends of the side members. The shaft 11 may be driven from any suitable source of power, for example the belt pulley 13 shown in the drawings. Also, of course, an electric motor may be employed and for some purposes I prefer an electric motor for the reason that it may be readily supplied with a time switch

to insure that each mold is given the same period of vibration, thereby insuring uniformity in the product. The springs 9 do not rest on top of the ratchet, but are positioned to be engaged by the face of the tooth on the side of the ratchet toward the table. Otherwise stated, the springs are long enough for their ends to project just within the circumference of the circle defined by the outermost edge of the ratchet teeth. Hence, as

each tooth passes the end of the springs the free ends of the springs will be lifted, and then pass off the tooth into space where it can freely vibrate for a moment.

The ends of the springs are attached to the under side of the table by any suitable means. For example, they may be riveted at their far ends and held against the adjacent edge of the table by yokes 14, to thereby avoid the necessity of putting a hole through the springs at a point where the greatest strain comes.

By having the springs but slightly overlapping the teeth of the ratchet as described, the ratchet may be rapidly rotated without the expenditure of much power. Also, the amplitude of direct movement is relatively small. The rotation of the ratchet thus effects a series of rapid knocks against the end of the springs, which serve to set up in the springs a vibration very much like that set up in a tuning fork, which vibration is imparted to the table and consequently to the mold or other article resting on the table.

I have found that the use of the vibrating table in the molding of concrete blocks entirely obviates the necessity of tamping the material in the molds and that a much denser and more uniform product can be obtained.

In Fig. 5 I have shown a modification of the vibrating table of Fig. 1 to adapt it for use in connection with the molding of drain tile. As here shown the table 4a is provided with a series of transversely extending cores 16 for the pipe molds. As shown, the cores are made of hollow

steel tubes somewhat tapered. The cores are fastened at their larger ends to the table by means of rings 17 beneath the table. Resting on the table and surrounding the core is a base member 18 for shaping the end of the tile. This base member consists of a cast iron ring resting at its inner edge on the table and extending thence upwardly and outwardly to give a tapered neck to the drain tile.

10 The upper face of the ring is formed with a shoulder 19 and an outwardly extending horizontal flange 20 on which the outer member 21 of the pipe mold is supported. This outer member may consist of a length of cylindrical pipe of the proper diameter or if desired the mold may be split on one side to permit its ready removal from the pipe after it is set sufficiently.

15 The table mounting and its vibrating mechanism is the same as employed for the plain table.

20 In using this form of the device the rings 18 and the outer mold sections 21 are assembled on the cores and the intervening space filled with cement mixture. The vibrating mechanism is set in operation, causing the cement to settle, the

25 duration of the vibration determining the density of the resulting pipe. As soon as the vibration of the table is stopped the base rings and outer mold members with the contained drain pipe are stripped off the cores and set aside for the tile

30 to set. While the vibration of the table causes the cement to settle into a compact mass between the core and the outer section of the mold, I find that the molds are not so difficult to remove from the cores as when the mixture is tamped to the

35 same density. This is doubtless due to the relative vibration between the outer mold member and the cores which are fixedly supported on the cross channel. The relative movement is very slight, but it is sufficient to prevent a strong adhesion between the cement and the core, particularly as the molded tile are removed from the machine immediately upon stopping the vibrator.

40 In Figs. 6 and 7 I have shown a modified form of mechanism wherein the core and the table

45 are subjected to vibration. In this construction the vibrating table is substantially the same as in the mechanism illustrated in Figs. 5 and 6. The core 22 is detachably supported on the table by means of lugs 23 and adapted to be connected

50 to the table by means of bolts inserted in holes in the table. The core itself is preferably expansible and consists of a piece of sheet steel rolled to form a cylinder with the edges of the sheet slightly overlapping. Attached to one of

55 the overlapping edges is a vertical angle member 25 with its radial face substantially flush with the edge of the steel cylinder. Attached to the other of the overlapping edges, but spaced back from the edge a slight distance is another vertical angle member 26. Extending between the two angle members is a plate or bar 27 whose upper end projects beyond the top of the core and is provided with a handle 28 whereby the bar may be turned.

60 The two angle members 25 and 26 are held against the sides of the bar by means of a spring 29 supported on a bolt 30 in the inner edges of the two angle members in the manner shown in

65 Fig. 6. A similar construction is provided near the bottom of the core so that on rotation of the bar the core will be expanded and contracted uniformly throughout its length.

70 The mechanism so far described may be employed in molding pipe in the same manner as the arrangement illustrated in Fig. 5. I prefer,

however, to independently vibrate the core. This is accomplished by means of a second ratchet shaft 31 mounted for rotation on the cross member 24 and preferably driven from the shaft 11 by means of a belt or sprocket chain. The shaft 31 is provided with a pair of ratchets 32 and engaging the teeth of the ratchets are a pair of metal bars of spring steel 33 which extend downwardly from the top of the core. The bars are not attached directly to the core, but are preferably suspended from the upper ends of a second pair of spring bars 34 which are in turn supported at their lower ends on brackets 35 attached to the inner face of the core. The ends of the bars 33 overlap the ratchet wheels just sufficient for the uppermost teeth on the ratchets to engage the ends of the bars and impart to them a slight lateral movement as the ratchet wheels are turned. The vibration produced by the effect of the ratchet sets up in the springs an oscillation which imparts to the core a rapid vibration of slight amplitude.

5 By vibrating both the core and the mold the desired density of the drain tile may be secured more rapidly than when only the table is vibrated and also a greater uniformity throughout the height and thickness of the drain tile is obtained. The arrangement of Fig. 7 is particularly applicable to large tiles, but may of course be used with smaller tiles if desired. The contractile 15 core permits the ready removal of the tiling. This construction is also particularly useful with the larger sizes of tile.

In Fig. 8 I have illustrated a complete molding apparatus for molding drain tile. This apparatus 35 includes a vibrating table of the kind shown in Figs. 6 and 7, with which there is combined an end-shaping attachment whereby after the charge of cement has been caused to settle in the mold by the action of the table, the upper end 40 of the pipe may be shaped to give the proper contour to the end face of the pipe so that the several pipe sections will project one into the other when laid.

45 As shown, this apparatus comprises an elevated framework 50 supported on standards 51 rising from the side channels 2 of the main table. The frame comprises a pair of channels 52, 53, respectively, at each side of the table and fixedly attached to the inner upper ends of the uprights 50 51. The channels are spaced apart so that the upper flange of the channel 52 and the lower flange of the channel 53 form guides at each side of the frame, in which guides there is mounted for sliding movement in a plane parallel with the face of the table a carriage consisting of a plate 54 whose side edges rest on the upper flanges of the frame members 52 and a plurality of transverse channels 55 extending across the plate at each edge and at spaced intervals between, the 60 flanges of the channels being of a depth for their ends to move freely below the lower flange of the upper members 53. Attached to the under side of the plate 54 is a rack 56 which meshes with a pinion 57 carried by the axle of a hand wheel 58 suitably supported in brackets on the rear uprights 51.

65 The upper frame members 53 project forwardly beyond the forward frame members 51 a sufficient distance for their ends to overlie the centers 70 of the cores 22 when supported in position on the vibrating table.

75 At the forward end of the plate 54 a series of nuts 59 are welded or otherwise secured to the under side of the plate in positions corresponding

with the centers of the molds when the carriage is shifted to its forward position, as illustrated in Fig. 8. Supported in each of the nuts 59 is a threaded shaft 60 carrying a hand wheel 61 by means of which it may be rotated. Attached to the end of the shaft 59 is a plate 62 of a diameter slightly greater than the diameter of the pipe to be shaped and attached to the outer face of the plate near its periphery is a shaping ring 63 formed of sheet metal and bent to a shape corresponding with the footpiece 20 attached to the table whereby the upper ends of the pipes will be of a shape complementary to that of the lower ends of the pipes, as will be obvious.

15 The plate 62 is preferably detachably connected to the end of the shaft so that plates of different sizes and with differently shaped rings may be employed.

In operating the apparatus the molds are filled 20 flush with the top as previously described, and cover 39 is put in place as shown in Fig. 6. The table and core are then vibrated, as described, for the proper length of time, thereby causing the settling of the material in the mold. The cover 39 is then removed and hand wheel 58 is operated to move the carriage from the dotted line 25 position shown in Fig. 8 to the full line position, thereby bringing the end-shaping rings over the respective molds. The hand wheel 61 is then operated to press the shaping rings down against the material in the mold, thereby shaping the end of the pipe to conform with the shape of the ring. After the end of the pipe is shaped the parts 30 are returned to the dotted line position, the core of the mold is contracted and the outer section of the mold stripped off the core with the pipe in the mold, in which it is allowed to remain until sufficiently set to be removed without damage.

I claim:

40 1. In a machine for molding cement pipe, the combination of a table, resilient supporting means therefor, a core mounted on the table, an outer mold section surrounding said core thereby forming an annular mold for the pipe, means for 45 vibrating the table in one direction, and independent means for vibrating the core in a direction at right angles thereto.

2. In a machine for molding cement pipe, the

combination of a table, resilient supporting means for said table, a core mounted on the table, an outer mold section surrounding said core thereby forming an annular mold for the pipe, means for imparting to the table a desired frequency of vibration, and independent means for imparting to the core a different frequency of vibration.

3. In a machine for molding cement pipe, the combination of a table, resilient supporting means for said table, a core mounted on the table, an outer mold section surrounding said core thereby forming an annular mold for the pipe, means for imparting to the table a desired frequency of vibration, and independent means for imparting to the core a higher frequency of vibration.

4. In a machine for molding concrete articles, a mold support, means for resiliently supporting the same, an elongated plate spring rigidly secured at one end to said support and projecting freely therefrom, and a toothed wheel mounted for rotation adjacent the free end of said spring, the end of said spring coating with the tips only of the teeth of said wheel whereby the spring is allowed to vibrate freely after each release thereof by said teeth.

5. In a machine for molding cement pipe, the combination of a table, means for resiliently supporting said table, an annular pipe mold mounted on said table comprising a core and an outer mold section surrounding said core, a flexible resilient member fixed at one end to said table and projecting freely therefrom, a second flexible resilient member fixed at one end to said core and projecting freely therefrom, and means for setting up vibrations in each of said flexible resilient members to thereby effect vibratory movements of said table and said core.

6. In a machine for molding cement pipe, the combination of a table, resilient supporting means therefor, a core mounted on the table, an outer mold section surrounding said core thereby forming an annular mold for the pipe, means for vibrating the table in the vertical direction and independent means for vibrating the core in the horizontal direction.

CHARLES DIETRICH.
